UNITED STATES PATENT OFFICE.

WILLIAM R. JEAVONS, OF CLEVELAND, OHIO.

DESIGN FOR A CONNECTING MEMBER FOR HYDROCARBON-STOVES.

SPECIFICATION forming part of Design No. 35,679, dated February 4, 1902.

Application filed December 4, 1901. Serial No. 84,706. Term of patent 7 years.

To all whom it may concern:

Be it known that I, WILLIAM R. JEAVONS, a citizen of the United States, residing at Cleveland, in the county of Cuyahoga and State of Ohio, have invented and produced a new and original Design for a Connecting Member for Hydrocarbon-Stoves, of which the following is a specification, reference being had to the accompanying drawing, forming part thereof, in which the single figure is a perspective view of my design.

The design as illustrated in the drawings has an embodiment *a* not unlike the capital letter **Y** when seen in side elevation; but in this instance the design is further marked and made distinctive and conspicuously origi-

nal by reason of stem *b*, surmounting the perpendicular arm *c* of the body *a* and having at its own ornamentation a threaded surface 2 and a reduced extremity 3, said stem standing out prominently above the body *a*, as shown.

What I claim is—

The design for a connecting member for hydrocarbon-stoves, substantially as shown 25 and described.

Witness my hand to the foregoing specification this 23d day of November, 1901.

WILLIAM R. JEAVONS.

Witnesses:

R. B. MOSER,
H. E. MUDRA.
